UNITED STATES PATENT OFFICE.

MORRIS BORRIS, OF NEW YORK, N. Y.

DESIGN FOR A LOUD SPEAKER.

Application filed August 10, 1927. Serial No. 23,036. Term of patent 3½ years.

To all whom it may concern:

Be it known that I, MORRIS BORRIS, a citizen of the United States, and a resident of the city of New York, borough of Manhattan, in the county and State of New York, have invented a new, original, and ornamental Design for Loud Speaker, of which the following is a specification, reference being had to the accompanying drawing, forming part thereof.

Figure 1 is a front perspective view of a loud speaker, showing my new design.

Figure 2 is a side perspective view of the loud speaker shown in Figure 1.

I claim:

The ornamental design for a loud speaker, substantially as shown.

MORRIS BORRIS.
